(57) **CLAIM**

The ornamental design for a rotor and field coil assembly, as shown and described.

DESCRIPTION

FIG. 1 is a front and side perspective view of a rotor and field coil assembly in a coupled state in accordance with my new design;

FIG. 2 is a side elevation view thereof;

FIG. 3 is a front elevation view thereof;

FIG. 4 is a rear elevation view thereof;

FIG. 5 is a rear and rear side perspective view thereof;

FIG. 6 is a front and side perspective view of the design shown in FIG. 1 in an uncoupled state;

FIG. 7 is a side elevation view thereof;

FIG. 8 is a front elevation view thereof;

FIG. 9 is a rear elevation thereof; and,

FIG. 10 is a top and rear perspective thereof.

The broken lines shown in the drawings illustrate portions of the rotor and field coil assembly that form no part of the claimed design.
